UNITED STATES PATENT OFFICE.

FRENCH E. DENNISON, OF BELOIT, WISCONSIN, ASSIGNOR TO NATIONAL REFRIGERATION CORPORATION, OF BELOIT, WISCONSIN, A CORPORATION OF DELAWARE.

REFRIGERATING APPARATUS.

Application filed July 21, 1926. Serial No. 123,992.

This invention relates to a refrigerating apparatus and more particularly to a refrigerating unit which may be used as a condenser or an evaporator.

5 One of the objects of the present invention is to provide a construction of a refrigerating device, such, for instance, as a condenser or evaporator unit in which the number of square feet of conduction and 10 radiation surface is increased to a maximum and at the same time the unit in itself is so constructed as to occupy a minimum amount of cubical space.

A further object of the invention is to 15 provide a refrigerating unit which is particularly adapted as an evaporator for use in connection with soda fountains in which the unit is mounted in a vertical position for maintaining practically uniform temperature from top to bottom.

A still further object of the invention is to provide a construction of a refrigerating unit in which the refrigerant passing through the same is so distributed throughout the unit as to maintain a uniform temperature at all points of the unit.

A still further object of the invention is to provide an improved refrigerating unit in which the refrigerant is caused to be 20 passed through relatively narrow channels which permit rapid evaporation to such an extent as to prevent flooding of the unit.

These and other objects are accomplished by providing a construction and arrangement of the various parts in the manner hereinafter described and particularly pointed out in the appended claims.

Referring to the drawings,

Fig. 1 is a side elevational view partly in 40 section of my improved refrigerating unit, and,

Fig. 2 is a cross-sectional view taken on the line 2—2 in Fig. 1.

The invention illustrated and described in 45 the present instance is an improvement on, or a specific application of the construction of my invention described and claimed in the copending application, Serial No. 120,355 filed July 3, 1926.

50 The present invention in addition to affording a maximum conduction in radiation surface to the refrigerant within the refrigerating unit, also provides the advantages of occupying a minimum cubical space

as pointed out in my copending application 55 above referred to.

The present invention is specifically directed to a refrigerating unit which is especially adapted for use in soda fountains or ice cream cabinets in which the cylindrical containers of the ice cream may be positioned within the unit and the unit by reason of its construction will maintain a uniform temperature from top to bottom.

In illustrating one embodiment of my invention for accomplishing these results, I have shown the same as comprising an outer tubular metallic or hollow casing 10 within which is mounted a snugly fitting tubular or hollow casing 11. The casings 10 and 11 70 are made of relatively thin metal and are of sufficient length to accommodate the entire length of an ice cream can or container.

The inner cylinder casing member 11 is provided with a plurality of V shaped peripheral grooves or passages 12. The grooves 12, of which there are three in number, are uniformly spaced from each other but on each convolution of the three grooves the pitch is gradually increased so that the 80 three grooves on the inner cylindrical member are spaced relatively further apart as the bottom of the refrigerating unit is approached, as clearly shown in Fig. 1.

The preferred method of making my refrigerating unit consists of taking two metal tubular members, one of which is adapted to snugly fit within the other. The peripheral surface of the inner tubular member may be grooved or cut on a lathe in a 90 manner well known, so as to form the passageways for the refrigerant. When the grooves or passages are cut on the inner tubular member, it is then inserted within the outer tubular member, after which the adjacent ends of both members are soldered or welded so as to completely seal the passages between the members. Obviously other methods may be employed in constructing my improved form of refrigerating unit and 100 still be within contemplation of my invention.

It will be readily understood that as the refrigerant circulates through these peripheral passages in the casing member 11, that 105 a gradually lesser amount of refrigerant is required to cool a greater volume of ice cream as it approaches the bottom of the

unit so that the temperature throughout the unit is substantially uniform from top to bottom, thereby maintaining the ice cream or other substance at a uniform temperature 5 throughout.

Formed on the upper end of the inner casing member 11 and communicating with the three passages 12 is an annular peripheral recess 13 which forms a distribution 10 chamber for the incoming refrigerant supplied thereto by the supply pipe 14 which in turn is connected with the expansion valve of the refrigerating apparatus.

The cylindrical casing members 10 and 11 15 have their opposite ends soldered or welded together as shown at 15. The lower ends of the peripheral grooves 12 communicate with and discharge the refrigerant into a peripheral recess 16 formed in the lower end of the 20 casing 11 adjacent the bottom thereof. This recess or chamber 16 is connected by a conduit 17 through which the refrigerant is discharged from the unit.

In the operation of the above described 25 device the refrigerant passes from the expansion valve through the conduit 14 into the distribution recess or chamber 13 where it is distributed through the peripheral grooves 12. As the liquid refrigerant is being circulated through the grooves 12 the absorption of heat becomes so rapid on account 30 of the relatively large radiation surface in comparison with the relatively small channels in the unit, that the liquid in a short 35 time becomes vaporized before reaching the channel or recess 16 in the bottom of the unit. On account of the grooves 12 being gradually spaced apart a greater distance toward the bottom of the unit, it will be readily seen 40 that the unit maintains a uniform temperature throughout or from top to bottom.

In illustrating one embodiment of my invention, I have shown the same as comprising two cylindrical casing members in making up my unit, but it will, of course, be understood that forms, other than that shown in the drawings embodying my principle of operation, may be made and still be within contemplation of my invention.

It will also be seen that by providing a construction of an expansion device of the form herein described in which the refrigerant is spread over a wide area of reduced cross section, the refrigerant must travel at a greater speed as compared with the speed at which the refrigerant travels in the conventional form of expansion coil or pipe commonly used. This, of course, is assuming that the same amount of refrigerant fluid 50 is passing through both devices.

With my present construction as above described, I increase the rate of transfer of heat from the storage casing to the inside of the expansion unit and thereby make the 55 same more efficient as compared with the

pipe expansion coil of large cross section now in use. In the pipe construction it is apparent that a large amount of expanding gas passes on through in the center of the pipe without coming in direct contact with 70 the heat transfer surface; when the gas contacting with the inner surface of the pipe has absorbed its quota of heat, it not only forms a barrier to the cold gas within it but rises in temperature and thereby reduces the 75 temperature difference between the outside and inside of the pipe wall, thus reducing the speed of the transfer of heat and the efficiency of the expansion coil.

While in the above specification I have described one embodiment which my invention may assume in practice, it will, of course, be understood that the same is capable of modification without departing from the spirit and scope of my invention as expressed in 85 the following claims.

I claim:

1. The combination of a refrigerating unit 90 adapted to be inserted in a closed circuit refrigerating system for changing the state of the refrigerant thereof comprising a double walled cylinder having a spiral passage formed between the walls, the inner and outer walls of said passage being arranged so close that a maximum of conducting area is afforded by said walls in proportion to the volume of said passage, means 95 for conducting refrigerant to said unit at one end of said passage in one state and means for conducting said refrigerant from 100 said unit at the other end of said passage in another state.

2. A refrigerating unit comprising a casing 105 having a spiral passage formed therein, said passage having a varying pitch.

3. A refrigerating unit having a chamber formed therein comprising a plurality of spirally arranged passages of varying pitch.

4. A refrigerating unit comprising a casing having a chamber formed therein, said chamber comprising a plurality of uniformly spaced spiral passages of gradually varying pitch whereby said refrigerant is unequally distributed over said unit for maintaining the unit at a uniform temperature 115 throughout.

5. A refrigerating unit comprising an outer cylindrical casing, an inner cylindrical casing snugly fitting said outer cylindrical casing, there being a passage formed on said inner cylindrical casing, of such a shape with respect to the longitudinal axis of the unit that a refrigerant passing through said passage unequally distributes said refrigerant for maintaining a uniform temperature 125 throughout said unit.

6. A refrigerating unit comprising a cylindrical casing, an inner cylindrical casing snugly fitting said outer casing, there being a spirally arranged passage formed in said 130

inner casing, the convolutions of the passage being so arranged that the refrigerant passing through said passage is unequally distributed throughout the area of said unit for maintaining said unit at a uniform temperature throughout.

7. A refrigerating unit comprising a cylindrical outer casing and a cylindrical inner casing snugly fitting said outer casing, a plurality of uniformly spaced apart passages of progressively varying pitch formed between said casings for unequally distributing the refrigerant passing therethrough whereby said unit is maintained at a uniform temperature throughout.

8. A refrigerating unit comprising an outer tubular casing and an inner tubular casing, there being a plurality of spirally arranged passages in said inner tubular casing, said passages arranged on said inner cylindrical casing in an uniformly increasing pitch as said passages approach the bottom of said unit whereby the refrigerant is unequally distributed over the area of said unit for maintaining a uniform temperature throughout the unit.

9. A refrigerating unit comprising a casing, a plurality of spirally arranged passages of gradually increasing pitch forming a chamber in said casing, an annular recess formed in the upper end of said casing and communicating with said passages for distributing the refrigerant in said passages,

and a recess formed at the bottom of said casing for receiving the refrigerant from 35 said passages.

10. A refrigerating unit comprising a tubular outer casing, an inner tubular casing snugly fitting said outer casing, there being a plurality of spaced apart passages 40 formed in said inner casing, said passages being arranged in a gradually increasing pitch as they approach the bottom of said unit, a recess formed in the upper end of said inner casing communicating with said 45 passages, and a recess formed in the lower end of said inner cylindrical casing for receiving the refrigerant discharged from said passages.

11. The combination of a refrigerating 50 unit adapted to be inserted in a closed circuit refrigerating system comprising a double walled cylinder having a spiral passage formed between the walls, the inner and outer walls of said passage being arranged 55 so close that a maximum of conducting area is afforded by said walls in proportion to the volume of said passage, means for conducting refrigerant to said unit at one end of said passage and means for conducting 60 said refrigerant from said unit at the other end of said passage.

In witness of the foregoing I affix my signature.

FRENCH E. DENNISON.
